KNIFE HOLDER

Morton S. Adler, Des Moines, Iowa

Application August 16, 1951, Serial No. 16,305.

Term of patent 14 years

(Cl. D44—29)

To all whom it may concern:

Be it known that I, Morton S. Adler, a citizen of the United States, residing at Des Moines, in the county of Polk and State of Iowa, have invented a new, original, and ornamental Design for a Knife Holder, of which the following is a specification, reference being had to the accompanying drawing, forming a part thereof.

Fig. 1 is a front perspective view of a knife holder, showing my new design.

Fig. 2 is a side elevational view of this knife holder, and

Fig. 3 is a top plan view.

I claim:

The ornamental design for a knife holder, as shown.

MORTON S. ADLER.
